PHOTOGRAPHIC MEANS FOR RECORDING SOUND

Filed Dec. 22, 1922

UNITED STATES PATENT OFFICE.

RUSSELL HART, OF LOS ANGELES, CALIFORNIA.

PHOTOGRAPHIC MEANS FOR RECORDING SOUND.

Application filed December 22, 1922. Serial No. 608,499.

My invention relates to means for photographically recording sound modulated light variations upon a moving sensitized film; and the salient objects are, first, to provide a source of light that is highly sensitive to sound waves, including the overtones, and capable of responding to quality vibrations as well as to intensity and pitch; second, to secure very high responsive speed of the light to sound variations; and, third, to afford facilities for photographically recording the responsive action of the light in such a manner as to constitute a complete and undistorted sound record.

Other highly important objects are to supply means for producing a sound record of great sharpness so as to permit, for example, of practically perfect reproduction of articulated voice; and to accomplish the recording at a film speed far below that hitherto possible, and corresponding to the speed commonly employed in the taking of motion pictures.

Additional objects and advantages of my invention will appear hereinafter, and while I show herewith and will describe a preferred form of construction to accomplish my objects, I desire it to be understood that I do not limit myself to such form, since various changes and adaptations may be made therein without departing from the spirit of the invention as hereinafter claimed.

It will be apparent that, in order to secure the results desired, the means employed must include; a source of light of high actinic value; the elimination of diffraction; very accurate focusing; and the prevention of all forms of distortion of the record so far as this can be done.

Hitherto a narrow slit in close proximity to the film has been used, and the modulated light has been focused thereon by various means. It is well known that light in passing such a slit is diffracted at each side thereof, and that the narrower the slit the greater will be the diffraction. It is impracticable to run a film directly against any known form of slit, and runners that space the film at least $\frac{1}{100}$ of an inch from the slit have therefore been employed. Both of these facts militate against sharpness of the record, and cause blurring in the reproduced sound.

The film speed that is normally employed in the taking of motion pictures is one foot

per second. To record articulated voice at this speed I have found that the slit must not exceed $\frac{1}{2000}$ of an inch in width to get fair results. If such a slit is used in the hitherto known way, the image, with the 60 relatively great diffraction that is present, when cast upon a film $\frac{1}{100}$ of an inch distant, will necessarily be blurred and thus make it impossible to secure good articulation in the reproduction.

In the present invention an image of the slit is thrown upon the film by means of a suitable achromatic lens combination, thus entirely obviating the effect of slit diffraction, and making it possible to reduce the 70 image to any desired degree of fineness and sharpness. The finer and sharper the image of the slit can be made to appear, the slower the film can be run, and I have found it possible with my improved means to satisfactorily record music and articulated voice at film speeds of one foot per second or even less.

In the accompanying drawing Figure 1 is a side elevational view of a typical arrangement of my invention, with certain parts broken away and in section;

Figure 2 is a sectional plan view taken on the line 2—2 of Fig. 1;

Figure 3 is a cross sectional elevation 85 taken on the line 3—3 of Fig. 1;

Figure 4 is a sectional plan view of a portion of the manometric flame apparatus employed as a source of light in the illustrated apparatus. This view is drawn to a larger 90 scale than those previously mentioned;

Figure 5 is an enlarged elevational detail of a portion of the means employed for adjusting the position of the manometric flame;

Figure 6 is a fragmentary sectional elevation taken on the line 6—6 of Fig. 2;

Figure 7 is an enlarged end elevation of a preferred form of optical slit, and the means employed for adjusting its position angularly and transversely, and

Figure 8 is a fragmentary elevation of a film with a photographic sound record thereon, as produced by my improved means.

Similar numerals refer to similar parts 105 throughout the several views.

Before passing to the detailed description of my apparatus it should be understood that the present invention involves only the means for photographically record- 110

ing sound. It does not concern itself with the reproduction per se, for which practical methods have been devised.

In the embodiment of the invention selected for illustrative purposes the apparatus is mostly contained within an elongated light-proof box-like structure, or camera, 8, preferably supported by table legs of which one is shown at 9. The camera is 10 interiorly divided by a transverse partition 10, forming two main chambers to which access is had through the hinged trap doors 11 and 12. Above and below the right hand chamber of the camera are reel boxes 13, 15 having side opening doors 14, and communicating with the camera only by means of small narrow slits 15 for the passage of the photographic film strip 16.

In the present instance I have selected a 20 manometric flame 17 as the source of light. This may be an oxy-acetylene, or any other suitable flame of high actinic value, properly arranged for sound modulation. As illustrated the modulating apparatus comprises the horn 18, diaphragm box 19, diaphragm 20, and gas burner 21.

The combustible gas, as acetylene, is stored in tank 22 and passes to the burner through a regulating valve 23, hose 24, and 30 nipple 25. Similarly oxygen is supplied from tank 26 through regulating valve 27, hose 28, and nipple 29.

The combustible gas in the burner is in 35 free communication with one side of diaphragm 20 through tube 30. The sound receiving horn is in free communication with the other side of this diaphragm through tube 31. Sound waves entering the horn impinge on the diaphragm and cause it to 40 vibrate responsively. This modulates the gas pressure in the burner and produces a manometric effect upon the flame. The respective static gas pressures in the burner are preferably so adjusted as to produce 45 a thin, elongated, needle-pointed flame of great actinic value. In this way the modulating effect of the diaphragm may be made to vary the length of the flame in accordance with the character of the sound waves received in the horn.

At the point 32 an extremely tenuous optical slit is adjustably mounted. This may be made by depositing platinum or other suitable opaque substance upon a piece of 55 glass 33, as shown at 34, and then making a very fine line scratch 35 through this opaque deposit.

In my improved arrangement light from the flame passes through a suitable 60 condensing lens combination at 36 and is focused upon slit 35. The image of the illuminated slit is then thrown upon film 16 by means of a suitable achromatic lens combination 37. Since the film and its sensitized 65 coating is sufficiently transparent, the focus-

ing at this point may be accomplished by means of a microscope 38, co-axial with the camera, and permanently mounted thereon. It is possible to secure an exceedingly sharp focus in this way.

Obviously various adjusting means are required to secure the desired results. These are roughly indicated in the drawing but the co-operating parts should be accurately made in a manner permitting of exact manipulation.

The flame preferably should intersect the axis of the camera. The illustrated means of accomplishing this is by mounting the burner on the bent arm 39 pivoted in the 80 camera axis. This arm is engaged by the channelled fitting 40 and may be given any desired angular position by means of the hand wheel 41 which is in fixed co-operative relation therewith. Transverse adjustment of the arm is permitted by slotting it as at 42 in Fig. 5. The through bolt 43, and wing nut 44, serve to clamp these several parts in place when this adjustment is complete.

A counter weight 45 is provided for 90 obvious reasons, and the felt washer 46 and light coil spring 47 are furnished to close the elongated slit 48 where tube 31 passes through the side of the camera box. The described arrangement allows a considerable 95 range of angular and transverse adjustment of the burner.

As shown in the drawing the condenser is focused by means of hand wheel 49, 100 pinions 50, and rack bars 51; the condenser being mounted on the frame 52 which is 105 slidable on rails 53.

Optical slit 35 is positioned vertically by means of the screw 54, and angularly by the gear 55 and worm 56, operated by hand 105 wheel 57.

Lens combination 37 is mounted in the telescoping tube 58 and is focused by means of the rack 59, pinion 60, and hand wheel 61.

The form of microscope shown is focused 110 by means of the barrel screw 62.

Other features of the camera box proper include the small hooded inlet ventilators 63, below the flame, and the large hooded outlet ventilator 64 above it.

For photographically recording sound the film strip must be given a continuous uniform motion, and I prefer to use a synchronous electric motor for this purpose. The driving means should be positive in 120 character and the film must be constrained to lie perfectly flat at the point where it is being exposed. It must also be prevented from "chattering" or vibrating as the result of friction.

I employ ordinary reels 65 for the film; and any suitable type of feed sprockets 66, guide rollers 67, and pressure gate device 68. The feed sprockets are gear connected as shown at 69, and the driving power is ap- 125 130

plied to sprocket shaft 70, as by pulley 71. The other sprocket shaft 72 also carries a pulley 73, by means of which the take-up reel is yieldingly driven.

5 While being exposed, the film in the gate mechanism passes between two polished plates 74 and 75. These are pressed together by light spiral springs 76 surrounding the guide screw studs 77 in the manner common 10 to the art. Flatness of field is positively secured in this way, the exposure being had through small apertures in the plates in front of the film, as indicated at 78.

In operation the slit must be maintained 15 in parallel relation to the flame at the focused image of the latter. The length of the camera should be kept as small as possible to reduce the effect of vibration, and the apparatus should be rigidly supported in such 20 a manner that delicate adjustments can be made and maintained. The manometric flame may be used either in a horizontal position as shown, or in vertical position.

As described, and illustrated in Fig. 8, the 25 sound record comprises an exposed area 79 bounded on one side by the base line 80, and on the other side by a very irregular curve 81 corresponding to the complex shape of the sound waves. There is comparatively little variation in density throughout area 79, and for reproduction of sound reliance is chiefly had upon the variation of the ordinates of the curve. The modulated manometric flame however does vary somewhat 30 in intrinsic brilliancy, and this effect is recorded by corresponding changes in the density of the record which have their proportional effect upon the reproduced sound.

Instead of employing a light source modulated as here illustrated, it is perfectly feasible with my apparatus to make use of any suitable light source, and any known means of modulating the same by sound. Thus it is possible to employ a light source of fixed 45 dimensions, modulated wholly with respect to its intrinsic brilliancy. Such a source might comprise an incandescent filament operated at a very high temperature, and modulated electromagnetically. In such case 50 the photographic sound record would consist of an exposed band of constant width, but varying greatly in density. Such a record might be said to be "in and out" of the film as distinguished from the "back and 55 forth" type herein shown.

Having thus fully described my invention in a manner that will be readily understood, I claim;

1. Sound recording apparatus comprising; means for producing an attenuated actinic flame; a photo-sensitized surface, means for moving said surface at a uniform veloc-

ity; an intermediate opaque screen having a tenuous optical slit parallel to the flame, whereby a thin beam of actinic rays from the flame may be thrown upon said surface transversely to its direction of motion; and means for modulating the visible length of said flame by sound waves, to vary the width of said beam.

2. Sound recording apparatus comprising; means for producing an attenuated actinic gas flame; a photo-sensitized surface; means for moving said surface at a uniform velocity; an intermediate opaque screen having a tenuous optical slit parallel to the flame, whereby a thin beam of actinic rays from the flame may be thrown upon said surface transversely to its direction of motion; means for variably positioning the slit 75 transversely and angularly in its own plane; and means for modulating the visible length of said flame by sound controlled variations in the pressure of its combustible gas supply, to vary the width of said beam.

3. Sound recording apparatus comprising; means for producing an attenuated actinic gas flame; a photo-sensitized surface; means for moving said surface at a uniform velocity; an intermediate opaque screen having a tenuous optical slit parallel to the flame, whereby a thin beam of actinic rays from the flame may be thrown upon said surface transversely to its direction of motion; means for variably positioning the slit 80 transversely and angularly in its own plane; and an acoustic diaphragm in contact with the combustible gas supply of the flame adjacent its burner, whereby the visible length of the flame may be modulated by sound 85 waves, to vary the width of said beam.

4. In sound recording apparatus, a sound controlled actinic flame device comprising; a burner having independent supply connections for oxygen and combustible gas; and an acoustic diaphragm in contact with the combustible gas supply adjacent the burner, whereby the visible length of the flame may be modulated by sound waves.

5. In sound recording apparatus, a sound controlled actinic flame device comprising; a burner tip having a tubular outer shell adapted for connection to an oxygen supply; a concentric inner tube terminating within said shell adjacent its outlet, and adapted for connection to a combustible gas supply; and a chamber communicating with said inner tube adjacent the burner tip and having an acoustic diaphragm therein whereby the pressure of the combustible gas 110 may be modulated by sound waves, to vary 115 the visible length of said flame.

RUSSELL HART.
